UNITED STATES PATENT OFFICE.

JEFFERSON M. CLOUGH, OF NEW HAVEN, CONNECTICUT, ASSIGNOR TO THE
WINCHESTER REPEATING ARMS COMPANY, OF SAME PLACE.

MAGAZINE FIRE-ARM.

SPECIFICATION forming part of Letters Patent No. 294,581, dated March 4, 1884.

Application filed December 15, 1883. (No model.)

To all whom it may concern:

Be it known that I, JEFFERSON M. CLOUGH, of New Haven, in the county of New Haven and State of Connecticut, have invented a new Improvement in Magazine Fire-Arms; and I do hereby declare the following, when taken in connection with accompanying drawings and the letters of reference marked thereon, to be a full, clear, and exact description of the same, and which said drawings constitute part of this specification, and represent, in—

Figure 1, a side view of the arm complete; Fig. 2, a section through the receiver; Fig. 3, a side view with the butt-stock and fore-end removed; Fig. 4, a perspective view of the forward end of the magazine-tube; Fig. 5, a transverse section on line *xx*; Fig. 6, a transverse section on line *yy*. Fig. 7 illustrates modification of the shape of the forward end of the magazine; Fig. 8, a perspective view of the trigger-guard plate detached; Fig. 9, a longitudinal horizontal section in a central line through the forward end of the magazine-tube.

25 This invention relates to an improvement in that class of magazine fire-arms in which the magazine is arranged in the stock in rear of the barrel and opens below the longitudinally-movable breech-piece, and so that when 30 the breech-piece is open the column of cartridges is forced forward by the spring in the magazine, to present the foremost cartridge into a position forward of the front face of the breech-piece, and so that when the breech-piece is returned it will force said foremost cartridge into its chamber in the barrel, and particularly to the arm known as the "Hotchkiss gun." As heretofore constructed, this arm has been made with the butt-stock and 35 fore-end complete in one piece, the mechanism of the arm being located within the stock. This construction necessitates cutting away a large portion of the wood. This cutting away of the stock is not only expensive, but weakens 40 the stock throughout the receiver portion. Again, an arm in which the fore-end and butt portion are in a continuous piece has a more clumsy appearance than when a metal receiver is introduced between the butt portion and the

fore-end, notwithstanding the general outline 50 of the arm may remain the same.

The object of this invention is to construct the arm with a metal receiver with which the magazine-tube may be permanently engaged, and so that the butt-stock may be attached to 55 the receiver independent of the fore-end, and the fore-end attached to the receiver independent of the butt-stock.

To this end the invention consists in the construction of the receiver and forward end 60 of the magazine-tube, whereby the magazine-tube is located by its connection with the receiver, and secured thereto substantially independent of the butt-stock, and as more fully hereinafter described.

A is the receiver, constructed with a tang, B, at the rear end, similar to the receiver in other arms, to extend back onto the top of the butt-stock C and aid in securing the butt-stock to the receiver. At the forward end, D, the 70 receiver is constructed for the attachment of the barrel E, in the usual manner. Longitudinally through the receiver is the guideway F for the breech-piece, into which is a side opening, G, for the insertion of cartridges or the 75 ejection of shells, also in the usual manner for this class of arms. Into the bottom of the recess G an inclined passage, H, opens for the introduction of cartridges to the magazine-tube I, or for the presentation of cartridges 80 from the magazine into a position in front of the breech-piece. This inclined passage-way or mouth of the magazine terminates at a, where a shoulder is formed, against which the magazine-tube will abut, as shown in Fig. 2. 85 In rear of the extreme forward end of the receiver, and on each side, is a vertical shoulder, b, in outline shaped corresponding to the shape of the fore end, and so that the fore-end L will abut against that shoulder.

The trigger-guard plate M is of usual form, fitted with the guard N for the protection of the trigger O. This strap is of length to extend forward into the rear end of the fore-end L and rearward into the butt-stock, as seen in 95 Fig. 2, and is also constructed to fit a corresponding recess in the under side of the receiver, as seen in Figs. 5 and 6. Near its for-

ward end it is constructed with a lug, P, and through the sides of the receiver and the lug a screw, R, passes. Near the rear end of the receiver a like lug, S, is formed on the strap, 5 through which and the receiver a screw, T, passes. These two screws serve to secure the guard-strap to the receiver firmly, so as to become substantially a part of it. Through the forward end of the strap and through the fore- 10 end L into the bottom of the receiver a screw, N, is introduced, by which, together with the lug W on the receiver, which enters a corresponding recess in the fore-end, the fore-end is secured to the receiver. Forward of the receiver the usual bands are applied, as seen in 15 Fig. 1. Near the rear end of the guard-strap a screw is introduced to secure that end to the butt-stock, in the usual manner.

The forward end of the magazine is constructed as seen in Fig. 4—that is, with an 20 enlargement, b', and upon the under edge of this enlarged portion is a tongue, d. In the receiver, at the rear end of the mouth H, a recess, e, is made corresponding to this enlarged 25 part b' of the forward end of the magazine-tube, and at the bottom the recess is open to receive the tongue d between the two sides of the opening, as seen in Fig. 6, and so that the tube passed inward from the rear end of the receiver, its enlarged forward end enters and 30 fits closely the seat thus prepared for it at its junction with the mouth H of the magazine, and thus locates the tube and holds it in its proper relation to the mouth. The tongue d 35 forms a shoulder, f, at the rear, and against this shoulder a corresponding shoulder or shoulders, g, on the lugs h, which are a part of the trigger-guard, fit and bear.

The magazine-tube I is first introduced with 40 its end located by the seat formed in the receiver, as before described, then the trigger-guard plate is introduced to bring the shoulder g against the shoulder f on the tube; then the trigger-guard, secured, holds the magazine 45 firmly in its position. The magazine-tube extends rearward and downward, inclined corresponding substantially to the incline of the butt-stock, and so as to enter a corresponding recess in the butt-stock, and the butt-stock is 50 passed on over the tube into its position between the tang B and the trigger-guard against the rear end of the receiver. By this construction I give to the arm a general appearance similar to that of the Winchester arm, 55 the sides of the receiver being exposed substantially as in that arm. This construction of the receiver so as to locate and hold the magazine-tube enables the assembling of all the metal parts of the arm independent of the 60 stock, and avoids a large part of the expense of stocking the gun without adding materially to the metal parts of the arm.

While I prefer to construct the end of the magazine with the tongue at the bottom, which 65 will serve to locate it circumferentially, the

end of the arm may be made of angular shape—say polygonal, say as in Fig. 7—and the recess of corresponding shape, it only being essential that the forward end of the magazine and the recess in the receiver in which it fits shall 70 be of such shape as to positively locate the magazine-tube in its proper relation to the mouth, and so that when in place the mouth forms a continuation of the tube forward.

If the receiver were exposed its entire length 75 between the butt-stock and the fore-end, it would be so long as to detract materially from the symmetrical appearance of the arm; but by forming the shoulder b in rear of the extreme forward end of the receiver, I extend 80 the fore-end rearward so far as to apparently shorten the length of the receiver and produce the appearance of the receivers in other classes of magazine-arms—such, for instance, as the Winchester arm. 85

As this invention does not in any particular relate to the lock mechanism of the arm, I have not shown that mechanism any further than to show the trip or check i in the magazine-tube, which is operated by the trigger to 90 hold back the column of cartridges.

I claim—

1. In that class of magazine fire-arms in which the magazine is located in the butt-stock and opens forward into the receiver, a receiver 95 constructed to receive a butt-stock independent of the fore-end, and with the mouth through which the cartridges are introduced to the magazine, or into which the cartridges are successively forced from the magazine, the 100 rear end of said mouth constructed to form a shoulder, a, and with a recess, e, in rear of it, and of other than cylindrical shape, combined with a magazine-tube, its forward end constructed of corresponding other than cylindrical shape, so as to fit said recess and abut against said shoulder, whereby said magazine-tube is located in its proper relation to the mouth, irrespective of the butt-stock into 105 which it extends, substantially as described.

2. The receiver constructed to receive the butt-stock independent of the fore-end, the trigger-guard plate arranged between the two sides of a receiver, and so as to form substantially the bottom thereof, said plate extending 110 rearward and fitted for attachment to the butt-stock, and forward fitted for attachment to the fore-end, the receiver constructed with a mouth through which the cartridges may be introduced to the magazine, or into which the cartridges may be successively forced from the magazine, the rear end of said mouth constructed to form a shoulder, a, and with a recess in rear of it, combined with a magazine-tube, its forward end constructed to fit said 115 recess and abut against said shoulder, whereby said magazine-tube is located in its proper relation to the mouth, irrespective of the butt-stock into which it extends, with a shoulder, 120 g, on the trigger-guard plate, constructed to 125

130

engage with a corresponding shoulder, *f*, on the magazine-tube, in rear of its forward end, substantially as described.

3. In a magazine fire-arm, the receiver constructed with the mouth *H*, through which the cartridges are introduced to the magazine, and into which the cartridges are successively presented from the magazine, said receiver constructed at its rear end to receive the butt-

stock, and with a vertical shoulder, *b*, in rear to its forward end, against which the fore-end *L* will abut, whereby said fore-end extends to a point in rear of the forward end of the receiver, substantially as described.
